US00D836395S

(12) **United States Design Patent** (10) **Patent No.:** **US D836,395 S**
(45) **Date of Patent:** **** Dec. 25, 2018**

(54) **CONTAINER**

(71) Applicant: **YETI Coolers, LLC**, Austin, TX (US)

(72) Inventors: **Roy Joseph Seiders**, Austin, TX (US);
Matthew Joseph Petrillo, Austin, TX (US);
Kyle Ellison, Austin, TX (US)

(73) Assignee: **YETI Coolers, LLC**, Austin, TX (US)

(**) Term: **15 Years**

(21) Appl. No.: **29/606,307**

(22) Filed: **Jun. 2, 2017**

(51) **LOC (11) Cl. 07-01**

(52) **U.S. Cl.**

USPC **D7/510; D7/511; D7/532**

(58) **Field of Classification Search**

(57) **CLAIM**

The ornamental design for a container, as shown and described.

DESCRIPTION

FIG. 1 is a top, front, right perspective view of a container showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, right perspective view of a container showing our new design in an alternate configuration;

FIG. 9 is front view thereof;

FIG. 10 is a rear view thereof;

FIG. 11 is a right side view thereof;

FIG. 12 is a left side view thereof;

FIG. 13 is a top view thereof; and,

FIG. 14 is a top, front, right perspective view of a container showing our new design in a second alternate configuration. The broken lines immediately adjacent to the shaded area represent unclaimed boundaries of the design.

1 Claim, 14 Drawing Sheets
